(57) **CLAIM**

The ornamental design for a bifurcated bed covering, as shown and described.

DESCRIPTION

FIG. 1 is a perspective top view of a bifurcated bed covering, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective top view of the bifurcated bed covering depicted with a seam covering fastener flap in a open position; and,

FIG. 9 is an environmental view of the bifurcated bed covering depicted as applied to a bed.

The broken line showing of a bed is for the purpose of illustrating environmental structure and forms no part of the claimed design.
